UNITED STATES PATENT OFFICE

WILLIAM E. GEDDES, OF ELLWOOD CITY, PENNSYLVANIA

WIRE BUNDLING MACHINE

Application filed January 23, 1932. Serial No. 588,376.

My invention relates to rod and wire bundling machines, the function of such a machine being to bind loose strands of rod or wire into easily handled units. This is customarily done by momentarily clamping the loose strands together and applying a tie wire by intertwisting its ends. These tie wires are spaced along the strands at sufficiently close intervals to form a more or less firm 10 bundle.

Although the men operating these machines try to bend the intertwined ends of these ties down it has been found quite impossible to prevent their tangling with those 15 of other bundles, tearing workmen's hands and being a general nuisance. These ties present further difficulties by sliding along the strands and bunching together, thus destroying their effectiveness.

One of my objects is to provide a bundling machine that binds loose strands of rod or wire together with ties by intertwisting their ends and then burying these ends in the strands. Ties applied in this fashion are 25 anchored against movement along the strand by their intertwined ends which, at the same time, are placed out of the way where they can do no harm. Other objects will be made apparent by the following disclosure.

Having reference to the accompanying drawings:

Figure 1 is a plan view of an example of a rod or wire bundling machine constructed according to my invention.

Figure 2 is an elevation of the machine showing its bundle discharging side.

Figure 3 is an elevation showing the end that receives the rod or wire to be bundled.

Figure 4 is a detail top plan of the tie 40 end twisting and burying mechanisms.

Figure 5 is a side elevation of Figure 4.

Figure 6 is a longitudinal cross-section of both the tie twisting and burying and tie placing mechanisms.

Figure 7 is a cross-section of the twisting arbor taken from the line VII—VII of Figure 6.

Figure 8 is a cross-section of the same taken from the line VIII—VIII of Figure 6.

Figure 9 is a cross-section of the twisting

arbor showing how the tie end clamping parts are pivoted together.

Figure 10 is a detail side elevation of the tie placing mechanisms, the ties in the machine being described comprising lengths of wire that are cut to size when needed, this figure showing a portion of the feeding mechanism for this wire.

Figure 11 is a cross-section on the line XI—XI of Figure 10.

Figure 12 is a cross-section on the line XII—XII of Figure 10.

Figure 13 is an end view of Figure 10.

Figure 14 is a detailed elevation of the mechanism that operates the mechanism that squeezes the bunched strands together.

Figure 15 is a cross-section on the line XV—XV of Figure 14.

Figure 16 is an elevation of the end opposite that shown in Figure 3.

Figure 17 is an elevation of the tie wire feeding mechanism and its control, showing the side opposite that shown in Figure 10.

Figure 18 is a cross-section taken from the line XVIII—XVIII of Figure 16, and showing in detail the device that automatically regulates the operation of the mechanisms that shift the strands and discharges them when formed into a bundle.

Figure 19 is a top plan of a portion of Figure 18.

Figure 20 is a cross-section taken from the line XX—XX of Figure 18.

Figure 21 is a cross-section taken from the line XXI—XXI of Figure 18.

Figure 22 is a side elevation of the clutch operating mechanism that puts the machine into and out of operation.

Figures 23 and 24 are cross-sections showing details of the clutch operating mechanisms shown in Figure 22.

Figure 25 is a front end elevation of Figure 5.

Figure 26 is a front end elevation of Figure 17.

The machine illustrated by these drawings is designed to bundle straight strands of wire, particularly wire that has been formed into binding wires for use in straw and hay baling machines and the like.

In detail, this machine consists of a bed or frame 2 supported upon legs 3 and 4 and resting in a floor pan 5. A drive shaft 6 is journaled in bearings 7 and 8 secured to one end of this frame, and a combination cam 9 and crank 10 are carried on one end of this shaft. A ram 11 is slidably positioned in the frame 2 by a gib 12 and has a roller 13 secured to its rear end by a pin 14, this roller being positioned for engagement by the cam 9.

The end of this ram opposite the end carrying this roller is provided with a steel extension 15. As the drive shaft rotates, the cam 9 engages the roller 13 and moves the ram 11 forward.

A gathering slide 16 is mounted opposite this extension 15 in a block 17 secured to the frame 2. This slide is provided with guide rods 18, 19 and 20 which pass through the back of this block and through an adjustable bar 21, this bar being carried on screw thread-ended rods 22 and 23 secured to the block 17. A compression spring 24 encircles the rod 19 and presses against the bar 21 and a plate 25 secured by set screws to the rods 18 and 20. Nuts are engaged on the ends of the rods 22 and 23, holding the bar 21 against the spring 24, putting tension on the slide 16.

The ram 11 carries a slide 26 held in position by a gib 27, a connecting-rod 28 being pivoted on a pin 29 to the crank 10 and on a pin 30 to this slide. The cam 9 is constructed so that when the drive shaft 6 is rotated the ram 11 and slide 26 do not change relative positions until the roller 13 has reached the high point on the cam. When this point is reached a tie should be in a position for fastening around the strands to be bundled.

The block 17 carries a pair of fingers 31 and 32 on pins 33 and 34. These fingers are provided with intermeshed segmental gears 35 and 36, the movement of each being thereby made dependent on the other. The gear 35 is fixed to the finger 32 by means of a bolt 37 operating in a slot in the gear, it being thereby possible to adjust the fingers' relative positions somewhat. These fingers have projecting ends 38 and 39 in which grooves 40 and 41 are cut, and are held with these ends apart by a torsion spring 42.

Stationary knives 43 and 44 are secured to the block 17 by binding screws 45 and 46 which pass through elongated slots in the knives, making them adjustable.

A lever 47 projects downwardly from the gear 36 and carries a roller 48 on a pin 49. A plate 50 is positioned between the block 17 and the frame 2 to act as a guide for the gathering slide 16 and a plate 51 is secured to the face of the block 17 on intervening strips 52 and 53 which bring this plate to a position where it acts as a guide and cover for the two fingers 31 and 32.

A rod 54 is fixed to a plate 55 secured to the ram 11 by screws 56 and 57, a block 58 being placed between the plate 55 and the ram to align the rod's end with the roller 48 carried on the end of the lever fixed to the top one of the fingers. A plate 59 is riveted to this rod and carries a projecting finger 60 beneath it, this finger being held by screws 61 and 62 which pass through elongated slots in the plate to provide for adjustment.

A bunch of strands of the wire to be bundled being placed between the end 15 of the ram 11 and in line with the gathering slide 16, and the tying wire being aligned with the grooves 40 and 41 in the ends of the fingers 31 and 32, it will be seen that by moving the ram 11 forward the tying wire will be forced back through the grooves of the fingers, drawing the tying wire from the top where an excess is provided for this purpose and pushing the slide 16 back.

As the end of the rod 54 is about to engage the roller 48 to operate the fingers, the projecting finger 60 being moved forward by the ram will engage a tubular knife 219, whose details will be explained later, and push it sufficiently far to cause the knife 44 to shear the tie wire. The rod 54 then contacts the roller 48 and causes the fingers 31 and 32 to move towards each other and carry the tie, that has just been cut, around the bundle. This will place the ends of the tie in a position where they may be grasped by the jaws of a twisting arbor 63.

Again referring to the ram 11, a knife 64 is pivoted intermediate its ends on a pin 65 held in a slot in the steel end 15 of the ram. A rod 66 is secured to the back end of this knife by a pin 67, and passes back through the ram 11. This rod has a right angular head projecting through an opening in the frame 2 so as to engage a pair of angle pieces 68 and 69 secured to the ends of this opening. When the ram is retracted the head of the rod 66 engages the angle piece 69, holding the knife substantially parallel to the strands being bundled. When the ram moves forward this head will engage the angle piece 68, thus forcing the knife 64 into the strands of wire being bundled, to form a pathway.

A lever 70 is pivoted intermediate its ends on a pin 71 carried by the ram 11 and has an angle bracket 72 which is held against a flat portion cut in the twisting arbor 63 by a torsion spring 73. This holds the mouth of this arbor in a vertical position for the reception of the ends of the tie. As previously stated, the slide 26 and ram 11 move forward together until the roller 13 reaches the high point on the cam 9, when the slide 26 will be individually moved forward by the crank 10. A cam member 74 is carried by an angle plate 75 that is bolted to a slotted plate 76 secured to the slide 26 through a second angle plate 77. The lever 70 carries a roller 78, on the

end opposite the end 72, which is engageable by this cam member. As the slide 26 moves forward the cam member 74 coacts with the roller 78 to rock the lever 70 out of engagement with the twisting arbor 63.

The arbor 63 has a revoluble head 79 carrying a cam 80 on its forward end, which engages a hardened pin in the end of a lever 81 pivoted to the arbor, the front of this lever 10 and the arbor forming a mouth 81^a which grips the tie wires. The back end of this head 79 is fixed to a pinion 82, the arbor and head being carried on the slide 11 in bearings 83 and 84. The arbor 63 has a shank end that 15 projects back through the head 79 and beyond the pinion 82, and carries a correcting finger 85. When the arbor has been revolved to intertwist the ends of the tie this finger will project upwardly for locking engagement by 20 the slot in the plate 76.

The pinion 82 is meshed with a gear 86 carried on the end of a shaft 87 which is journaled in bearings 88 and 89 secured to the ram. A bevel gear 90 is mounted on the 25 other end of this shaft and engages a second bevel gear 91 fixed to a stub-shaft 92 whose other end carries a segmental gear 93. This latter shaft is journaled in bearings 94 and 95, which are also secured to the ram.

This segmental gear 93 is engageable by a rack 96 carried by the slide 26, this rack having a double tooth 97 on one end of a series of teeth and a triple tooth 98 on the opposite end. The lever 81 operating the 30 mouth of the twisting arbor 63 pivots on a pin 99 held in a slot in the arbor. When the slide 26 moves forward the rack 96 rotates the segmental gear 93, this rotation being imparted, by the respective gears and shafts described, to the head 79 of the arbor 63. As this head rotates the cam carried by it engages the hardened pin in the end of the lever 81 and forces it out, causing the mouth 81^a of the arbor to grasp the ends of the tie. 45 Further movement of the slide causes the arbor to make one and three-quarters revolution so that the mouth of the arbor will come to rest in a horizontal plane.

A spiral cam member 100 is positioned on the shaft 87 for engagement by the double tooth 97 on the rack 96 as this rack passes out of mesh with the gear 93, this turning the shaft backwards slightly to open the mouth 81^a of the twisting arbor and obviating the need of closing the mouth to mesh the rack 96 with the segmental gear 93 properly when returning to rest position.

The rack is cut short and does not complete the revolving of the arbor 63. This is done instead by a latch 101 pivoted on a pin 102 carried on the side of the rack 96, this latch engaging a lug 103 secured to the top side of the segmental gear 93 and thus completing the revolving of the arbor 63, the segmental gear 93 being thereby rotated well

beyond the position where the rack 96 left it.

The segmental gear 93 is cut to receive the triple tooth 98 of the rack 96, when rotated backwards from its advanced position in order to open the mouth 81^a and consequently 70 remeshes the rack 96, when the same is retracted, in the proper position. The latch 101, during this backward movement, slides over the lug 103 is returned to its retracted position by a torsion spring 104.

The twisting arbor 63 and swivel head 79 are provided on their periphery with bumping pieces 105 and 106 which interengage to prevent the hardened end of the lever 81 80 passing beyond either the high or low point of the cam 80.

It will be seen from the description of the machine up to this point that a tie has been wrapped around the strands being bundled and its ends thrust into the mouth 81^a of the arbor 63. This arbor 63 has revolved one and three-quarters times to intertwist these ends and has come to rest with its mouth 81^a in a horizontal position, this mouth now being open because of the backward turn given the shaft 87 by the spiral cam 100.

A lever 107 is pivoted near one end on a pin 108 carried between mounts 109 and 110 which are secured to angle pieces 111 and 112, these pieces being secured to the bearings 83 and 84 by their cap screws. The end of the lever near this point has a roller 113 pivoted on a pin 114, the other end of the lever being deeply slotted to receive a burying finger 115. This lever is steadied by guide pieces 116 secured to the mounts. A plate 117 is positioned on the pin 108 over the angle piece 111 and carries a roller 118 near one end, on a pin 119. This plate 117 has a connecting-rod 120 fixed to it by a pin 121 and is constructed with an end 122 shaped for engagement with the roller 113 on the lever 107. The burying finger 115 is pivoted intermediate its ends on a pin 123 in a slot in the end of the lever 107, and has an end 124 fixed to the connecting-rod 120 by a pin 124, its opposite and inner end having a grooved head 128.

A stripper 125 is fixed on a pin 126 to the tip end of the lever 107 and projects to a point near the mouth 81^a of the arbor 63. This stripper has a grooved head 127 and is provided with an elongated opening 129 through which passes the head 128 of the burying finger 115.

As the slide 26 further advances with respect to the ram 11 a cam projection 133, formed on the outer edge of the slotted plate 76, engages the roller 113 and forces the end of the lever 107 outwardly, the opposite end carrying the burying finger 115 and stripper 125 being forced towards the end of the arbor 63. The grooved head 127 of this stripper is then forced past the mouth 81^a of this arbor, carrying the intertwined ends 130

of the tie therefrom to a position in front of the grooved head 128 of the burying finger 115. The rear end of this burying finger enters the mouth of the arbor and is steadied somewhat thereby. To prevent the tie from moving longitudinally along the strands during this stripping operation, a pair of projections 134 and 135 are carried by the steel end 15 of the ram 11 so as to engage the tie on both sides of its intertwined ends.

A plunger 130 is secured by a pin 131 to the slotted plate 76 and is held inwardly by a torsion spring 132. The end of this plunger is shaped to engage the roller 118 on the plate 117, thus rotating the plate in an anti-clockwise direction and forcing the burying finger 115 into the path cut by the knife 64, by means of the connecting-rod 120. The grooved head 128 of the burying finger has now partially buried the intertwined ends of the tie in the strands. Further movement of the slide 26 and plunger 130 causes the end 122 of the plate 117 to engage the roller 113 secured to the lever 107, this roller having now passed the projection 133 on the edge of the plate 76. The roller 113 is thereby forced inwardly, causing the other end of the lever 107 to move outwardly, the head 128 of the burying finger 115 now completely burying the tie's ends in the strands. This further rotation of the plate 117 causes a pin 136 carried thereon to enter a notch 137 in the outer edge of the plunger 130.

Further rotation of the axle 6 causes the crank 10 to pass its dead center and the slide 26 to begin its return movement. As stated, the pin 136 fixed to the plate 117 is in the notch 137 in the side of the plunger 130 and, as this plunger is drawn backwards, the plate is thereby rotated in a clockwise direction. As this plate is connected to the burying finger 115 by the connecting-rod 120 the finger is withdrawn from the strands by a motion exactly in line with that of its entrance. When once returned these parts are held in position by a spring 138, this spring not being depended upon to return the parts to position.

The roller 113 on the end of the lever 107 is engaged by a lever 139 pivotally secured at its back end upon a bushing 140, this bushing being secured between the plate 76 and a guide plate 141 by a bolt 142. This lever 139 has a cam edge 143 that engages a post 144 as the slide moves backwards, the end of this lever engaging the roller 113 forcing the latter inwardly to return the lever 107, which carries the burying finger 115 and the stripper 125, to its normal rest position. The spring 138 has an end 145 that serves to hold the lever 107 in its rest position. When the slide 26 reaches its rest position with respect to the ram 11, the ram itself begins its return movement. A pair of torsion springs 146 and 147 on the shaft 87

act as shock absorbers for the head 79 of the arbor 63 in both extremes of its movements.

The plunger 130 brings the arbor 63 to a stop at the end of its twisting operation 70 by means of a depending lug 148 which it brings into engagement with the correcting finger 85, the spring 132 absorbing the shock of this impact.

The arrangement for compressing the 75 strands while the tie is being applied consists of a lever 149 rocking on a shaft 150 which is journaled in bosses 151 cast on the leg 4. The top of this lever has a right angular end 152 that is engaged by a roller 153 journaled on 80 the pin 29 to the crank 10. The lever carries a dog 154 pivoted on a pin 155 which is secured to a stubby lever 156.

When the lever end 152 is not engaged by the roller 153 on the crank 10 the dog 154 85 is lifted by a pin 157 secured to the lever 156, which engages an upright 158 carried by an angle piece 159 riveted to the leg 4. A second dog 160 is fixed to the lever 149 by a pin 161, the other end of this pin being 90 secured to a trigger 162. This dog engages a lug 163 fixed to a bar 164, this bar passing between the two dogs 154 and 160.

The bar 164 has a slot 165 through which a pin 166 projects, this pin being fixed to 95 the lever 149. As the lever 149 is moved slightly forward by the crank 10, the dog 160 is thrown out of engagement with the lug 163 by means of the trigger 162 which rides in under a projection 167 fixed to the angle 100 piece 159. At the same moment the lever pin 157 is released from engagement with the upright 158, so that the dog 154 may engage one of a series of ratchet teeth 164^a 105 cut in the bar 164. Both of these dogs are urged to operative position by an interconnecting spring 168. The bar 164 is constantly urged toward the opposite side of the machine by means of a coil spring 169 which is fixed 110 between the pin 166 and a hook 170 secured to the end of the bar. The moment the dog 160 is forced out of engagement with the lug 163, the bar 164 is urged forward, the dog engaging one of the teeth 164^a.

A strand compressing finger 171 is secured 115 on the plate 51, carried by the block 17, by a pin 172. This finger has a long lever end 173 projecting down and fixed to the forward end of the bar 164 by a pin 174. A second strand compressing finger 175 is pivoted to the plate 51 and a pin 177 is fixed to the first finger and carries a roller 178 that contacts the back edge of the finger 175. When the bar 164 is thrust forward by the spring 169 the fingers 171 and 175 will be forced together. When the strands to be bundled are in the machine they are positioned between these fingers and will consequently be held tightly bunched together while the pre- 130

viously described tying operation is being performed.

These fingers are reopened, to permit movement of the strands for application of another tie, by a pin 179 that engages a plate 180 fixed to the bar 164. This pin is secured to a stud 181 fixed to a depending plate or bar 182 and a brace 183, the opposite ends of both depending from and being secured to 10 the ram 11. When the ram returns to its rest position the bar 164 will return with it, restretching the spring 169 and reengaging the dog 160 with the lug 163. The number and size of the strands between the two fingers 15 will determine which one of the teeth 164^a the dog 154 will engage during the forward motion of the bar 164.

As previously stated, the ties consist of lengths of wire which are cut by the machine. This wire is fed into position by means of a feeding mechanism that is mounted on a plate 184 having a bossed hub 185 which rocks on a pin 186, this pin being secured to a projection 187 cast on the leg 3. 20 A disk 188 carries a dog 189 on a pin 190 and is rotatably mounted on a stub shaft 191. This shaft also carries a gear 192 fixed to a ratchet wheel 193 that is engaged by the dog 189, this gear and ratchet wheel being 25 free to rotate with respect to the disk 188 were it not for the latter's engagement by the dog 189. This gear 192 is meshed with a pinion 194 carried by a shaft 195 that is journaled in bushings in a bracket 196, carried by the plate 184, and the plate itself. 30 The shaft 195 projects through to the other side of the plate 184 and carries a feed roller 197 to which is centrally secured a gear 198 which rotates with the shaft. A gear 199 is 35 also centrally secured to a feed roll 200 and is journaled on a pin 201 that is fixed to a lever 202. The upper end of this lever is pivotally fixed on a pin 203 carried by a lug 204 that is fixed to the top of the plate 184. 40 The gears 198 and 199 intermesh and drive the feed rolls 197 and 200 together. To prevent the feed rolls 197 and 200 from rotating backwards a dog 205 is pivoted on a pin 206 carried by an arm 207 that is fixed to the 45 plate 184 by a nut on the shank of the stub shaft 191. This dog is also in engagement with the teeth of the ratchet wheel 193.

The tie wire is straightened, before it enters the feed rolls 197 and 200, by means of a 50 set of straightening rolls 208, 209 and 210 that are rotatively carried by pins 211, 212 and 213 mounted on the plate 184. A guide 214, secured to the plate 184 below the straightening rolls, by a bolt 215, is drilled 55 perpendicularly to receive the tie wire which is thus held in alinement with the straightening and feeding rolls. A sharp ended dog 216 is pivoted on a pin 217 that is fixed to the plate 184 and is forced against the tying 60 wire by a torsion spring 218. The upper end 65

of the guide 214 is cut away to permit the entrance of this dog, this cutting also forming a flat section on the guide against which the wire is pressed by the dog so that the latter can secure a firm grip and prevent the wire's 70 backward movement through the guide.

The lug 204 that is fixed to the top of the plate 184 carries a tubular knife having a bore that is alined with the feed rolls 197 and 200 and the grooves in the projecting ends of the fingers 31 and 32. The upper end of this knife is in shearing engagement with the fixed knife 44 and, when the projecting finger 60 attached to the ram 11 engages this knife, the entire feeding mechanism carried by the plate 184 rocks slightly, causing the wire to 75 be cut.

A bar 220 is slidably mounted in the block 17 and has a groove 221 in alinement with the grooves in the ends of the fingers 31 and 32, this grooved bar forming a guide for the tie wire when being fed upwards. A depending bar 222 is fixed to this bar 220 and a rod 223 extends from its back end through a bore, 80 224 being the number of a spring in the block 17, with a head 225 on its back end. This head is pressed against the block 17 by a spring 224. The bar 220, being directly in the path of the strands being bundled, must be moved back when these strands are being 85 compressed by the fingers 171 and 175, this being done by the bar 222 which is engaged by a pin 226 on the rod 54.

To better control the strands being bundled, a plate 227, having a front end similarly shaped and alined with the gathering slide 16, is fixed at its rear end to the plate 25, this plate therefore moving with the slide 16.

When the strands to be bundled are pushed back into the tie wire there may remain an excess of the tie projecting above the knife 43. This is cut off by a knife 228 secured to a bracket 229 fixed to the ram 11. This knife cooperates with the fixed knife 43 to shear the tie and is preferably ground at an angle with its line of motion so that the cut end of the tie will be thrown clear of the machine. The knife 228 is secured to the bracket 229 by a screw 230, this screw passing through an elongated hole in the knife to provide for its 90 adjustment.

Before the tie wire goes into the feeding device just described, it passes beneath a shoe 231 carried on the lower end of a lever 232. This lever is pivoted a short distance from its upper end on the pin 181, and this upper end is secured through a pin 233 to a link 234 that is pivoted on a pin 235 carried by a boss in the leg 4. The shoe 231 is moved forward by the ram 11 and plate 182 to draw the necessary amount of wire from a supply reel. This amount may be varied by changing the lever- 95 age ratio of the rod 232.

The tie wire feeding device is operated by a link 236 that is pivotally secured on a pin 130

237 to the disk 188. The other end of this link is slidably arranged on a pin 238 fixed to the plate 182, this pin passing through a slot in the link. A block 239 is clamped to the 5 link 236, at its end closest to the disk 188, so as to project back and over a portion of this slot. This block is adapted to engage the pin 238, limiting its motion in the slot. The extent that this block limits the movement of this 10 pin determines the amount the disk 188 is rotated and, consequently, the number of teeth on the ratchet wheel 193 engaged by the dog 189.

In order that the strands being bundled 15 might have time to be moved clear from the path of the upwardly feeding tie wire, by means of the gathering slide 16 and plate 227, the pin 238 moves idly through the slot in the link 236 for a portion of the backward motion 20 of the ram 11. Upon the engagement of this pin with the end of the slot in the link 23 that is opposite the block 239, the disk 188 will be rotated. As the dog 189 engages the ratchet wheel 193 fixed to the gear 192, the 25 latter is also rotated. This motion causes the fed rolls 197 and 200 to feed a new length of tie wire into position.

The drive shaft 6 carries a sprocket wheel 240 connected by a chain 241 to a second 30 sprocket wheel 242, the second wheel being mounted on a drive shaft 243 positioned near the floor in bearings 244 and 245. These bearing are secured to the floor pan 5. The end of this drive shaft carries a crank 246. 35 A link 247 is fixed by pins 248 and 249 to universal joint blocks 250 and 251, the block 250 being pivoted on a pin 252 to the crank 246 and the block 251 similarly fixed to a lever 253 by a pin 254. This lever rocks on a stub 40 shaft 255 and carries a dog 256 having a tail end 257, the latter's front end being adapted to engage a ratchet 258 fixed to the hub of a large sprocket wheel 259. The lever 253 and this large sprocket wheel are positioned by 45 collars 260 and 261, and the ends of this stub shaft 255 are carried by bosses 262 and 263 cast in the legs 3 and 4.

The sprocket wheel 259 is connected to a smaller sprocket wheel 264 by a chain 265. 50 This smaller sprocket wheel rotates on a stub shaft 266 mounted on a leg 267, this leg being secured to the floor and strengthened by a brace 268. This stub shaft 266 passes through an elongated hole in the leg 267, so 55 that slack in the chain 265 might be taken up, and positions the wheel 264 to hold the top length of the chain 265 in a parallel position.

A strip of channel iron 269 has one end 60 carried by the leg 267 and the other by the frame 2 so as to be parallel to and a little bit above the top parallel length of the chain 265. This channel carries sheaves 270, pivoted on pins 271, by means of depending brackets 272. These sheaves prevent the top

length of the chain 265 from sagging out of position and are supplied in numbers suitable to the extent of this length. A shaft 273 is aligned with the channel iron 269 above and a little distance from its open side. This 70 shaft is rigidly positioned at one end by the frame 2 and at the other by a leg 274, this leg being braced to the leg 267 by an angle member 275.

A plate 280 having an open throat 281 is 75 rockably and slidably carried by the shaft 273. The open throat of this plate is aligned with the previously described strand tying mechanism and is adapted to engage the ends 80 of a bunch of strands being tied. In the case of many manufactured wire articles, the strands' ends are shaped to permit this engagement but, if not, the strands' ends may be temporarily bound by hand so that the open throat of this plate may engage the 85 bindings. A depending finger 282 is riveted to the bottom of the plate 280 so as to engage the chain 265 when this plate is rocked downwardly. A bracket 283 is fixed to the plate 90 near this finger and carries a roller 284 projecting into the open face of the channel iron 269, this limiting the rocking motion of the plate. With each complete revolution of the 95 drive shaft 6 this plate, when in engagement with the chain 265, will be shifted a distance equal to one-third of the circumference of the sprocket wheel 259. This will be done because the interconnected shaft 243 will also be revolved a complete revolution, operating the dog 256 and the three-toothed ratchet 258. 100

A depending rod 285 is fixed to the plate 280 at its upper end and to a sash cord 286 at its lower end, this cord passing around a sheave 287 pivoted on a pin 288 fixed to a bracket 289. This bracket is secured to the under side of the frame 2 by a clamp 290. This sheave changes the angle of the cord so that it can extend upward for connection to a weight. The plate 280 is normally held in raised position by a counterweight 291 that is fixed to the plate by an arm 292. When the ends of the strands being bundled are placed in the open throat 281, this plate will be rocked downward so as to engage with and be moved by the chain 265. When these 110 strands are discharged from the machine this plate will automatically rock upward to chain disengaging position and be returned by the weight fixed to the sash cord 286.

The device that discharges the strands, when bundled, from the machine includes a shaft 293 rocking in bearings 294 and 295.

The bearing 294 is carried by a bracket extension 296 cast in the frame 2, and the bearing 295 is carried by a leg 297 that is secured to the floor and strengthened by a brace 298. The shaft 293 carries a number of discharging arms 299, 300, 301 and 302. These arms have curved ends which rest below the normal path of the wire strands, as they are 120 125 130

shifted by the plate 280, on a strip 303 that is carried by brackets 304 that are fixed to the channel iron 269. These arms are all fixed to the shaft 293 for synchronous operation, and the arm 301 is fixed to a lever 305 that passes up over the shaft 293 and then angles downwardly. The end of this lever 305 is fixed to a block 306 by a pin 307, this block having a shank 308. A clamp 309 fixes a cable 310 to this shank, which extends down to a drum 311 where it is fixed by a screw 312, this drum revolving on the drive shaft 243.

Near this drum the drive shaft 243 carries an arm 313 to which a dog 314, having a tail 315, is pivoted by a pin 316. As the shaft 243 revolves the arm 313, the point of the dog 314 will engage a notch 317 cut in the drum 311. This revolves the drum and winds the cable 310 thereon, pulling the lever 305 downwardly and rotating the shaft 293 which synchronously raises the discharge arms. A set of skids 318, 319, 320 and 321 then receive the bundles and carry them away from the machine. As the arm 313 further revolves with the shaft 243, the tail 315 of the dog 314 engages a stationary tripper 322, this disengaging the dog 314 from the drum 311 and allowing the stripping arms to drop back so that their curved ends again rest on the strip 303.

The low projecting ends of the aforementioned skids are secured by angle pieces to a bar 323 which has one end fixed to the leg 297 by a bracket 324 and its other end fixed to the bracket extension 296 on the frame 2 by the arm 325. The skids are further strengthened by uprights 326 which are fixed to a bar 327 whose one end is carried by the leg 297 and whose other end is fixed to the frame 2.

The drive shaft 6 is driven by a pulley 328 through a clutch consisting of a notched sleeve 329 that is fixed to this pulley and a second notched sleeve 330 that is slidably fixed to the drive shaft 6. This pulley and its interconnected sleeve run freely upon the shaft 6 and are positioned by a washer 331 and nut 332. The sleeve 330 carries a projecting screw 333 that is adapted to be engaged by the inclined sides of a fork 334. This fork rocks on a stub shaft 335 which is fixed to the frame 2 and has a link 336 pivotally fixed intermediate its ends by a pin 337. The other end of this link is pivotally secured on a pin 338 to an arm 339. This arm is fixed to a shaft 340 carried in a journal 341 and rocked by a handle 342. This handle 342 projects up and beyond the shaft 340 and is connected by a pin 343 to a rod 344.

When this starting handle 342 is pulled away from the machine the interconnecting members will pull the fork 334 out of engagement with the screw 333. A coil spring 345 carried in the end of the shaft 6 between

pins 346 and 347 then pulls the sleeve 330 into engagement with the sleeve 329, this causing the shaft 6 to rotate with the pulley 328. The pin 347 extends into recesses 348 and 349 cut in the sleeve 330, the latter being slidably fixed to the shaft 6 by a key 350. When the fork 334 is moved towards the sleeve 330 its inclined side engages the screw 333 and draws the sleeve 330 along the shaft, against the tension of the spring 345, until it is disengaged from the sleeve 329 fixed to the pulley 328. Longitudinal motion of the fork 334 is prevented by a guide 352 having a slot in which the fork moves.

When a bunch of strands are placed in the machine with their ends in open throat 281 of the plate 280 they are properly positioned for application of the first tie. To prevent them from being shifted from this position during the first revolution of the shaft 6, which must operate the tying elements of the machine, a rod 353 is slidably mounted in brackets 354 and 355 fixed to the top of the bearings supporting the drive shaft 243. This rod 353 has a depending finger 356 on one end, that rests against the bearing 245. The other end of this rod carries an arm 357 that engages the tail 257 of the dog 256, upon sliding motion of this rod. The rod 353 also carries an arm 358 to which a roller 359 is fixed, this roller engaging a cam surface 360 cut in the face of the drum 311. When this drum rotates in the performance of its strand bundle discharging operation, the cam 360 will move the roller 359 so as to slide the shaft 353 and carry the arm 357 with it. The rod is held in this position by a latch 361 that is pivoted on a pin 362 to the bearing 245 and is forced by torsion spring 363 behind the finger 356 upon the latter's movement. When the rod 353 is in this position the arm 357 will be engaged by the tail 257 of the dog 256 and prevent its forward end engaging the ratchet 258.

A cam 264 is fixed to the end of the drive shaft 243 and engages a pin 365 secured in the latch 361. After a greater part of the first rotation of the shaft 6, the cam 364 engages the pin 365 and forces the latch 361 from behind the finger 356, the rod 353 being thereupon returned to its original position by a compression spring 366. The dog 256 can now function to rotate the stub shaft 255 and sprocket wheel 259 so that shifting operation of the strands is begun.

A rack for supporting the strands of wire being fed into the machine is positioned adjacent the latter's receiving end. This rack consists of a pair of beams 367 and 368 positioned in line with machine's tying mechanism and the open throat 281 of the plate 280. A sheet iron trough 369 is carried by these beams and the beams themselves are clamped to horizontal pieces of pipe 370 and 371 that are carried by a pair of elbows 372 and 373

on the ends of a pair of uprights 374 and 375. These uprights have floor plates 376 and 377 that are screwed to the floor.

The sheet iron trough carries an upstanding arm 378 that acts as a guide for the strands. The strands are further guided by the pieces 379 and 380. A second and shorter pair of beams 381 and 382 are positioned between the rack proper and the machine and are bolted to bars 383 and 384 that are clamped to the under side of the pipe 370 and the two beams 367 and 368. The two beams 381 and 382 carry a piece of sheet iron 385, the entire assembly functioning as a rack extension.

A regulating device provides a means which compels the various parts to perform their respective functions in sequence. This regulating device comprises a shaft 386 rocking in bearings 387 and 388, the first bearing being cast in the frame 2 and the second one being fixed to the upright 374 of the rack.

A lever 389 is fixed to the shaft 386 between the rack proper and the rack extension, this lever being depressed by the strands being bundled so long as they are on the racks. A second lever 390 is fixed to the other end of the shaft 386 at the opposite side of the tying mechanism. A second lever 391 is fixed to this shaft 386 and connected by a pin 392 to a link 393 to form a toggle joint. The other end of the link 393 is fixed to a sleeve 394 carried by the drive shaft 243, by a pin 395. This sleeve has an arm 396 which carries a pin 397 that projects parallel to the drive shaft 243 and is in line with the tail 315 of the dog 314 which operates the drum 311.

When the lever 389 is depressed by a bunch of strands placed in the racks, the shaft 386 is rotated, carrying the lever 390 downwards beneath the path these strands will take through the machine and throwing the toggle levers 391 and 393 to an off-center position. This off-center position will be opposite that shown in Figure 16. This position will rotate the sleeve 394 so that the pin 397 prevents the dog 314 from engaging the notch 317 in the drum 311, and consequently preventing rotation of this drum to throw the strands from the machine.

When the strands have been drawn to a position for application of the last tie, their ends will have been shifted past the lever 389 which will rise slightly, bringing the lever 390 into contact with the under side of the strands and throwing the toggle levers 391 and 393 into dead center position. This rotates the sleeve 394 so that the pin 397 cannot prevent the dog 314 from engaging the notch 317 in the drum 311, the drum consequently being rotated in the previously described manner and functioning to throw the strands from the machine.

A counterweight 398 on an arm 399 urges the levers 389 and 390 upwards, and a dog

401 engages a notch 402 in the drum 311 to hold the latter in its proper retracted position.

This regulating device also operates to prevent the tying wire from being fed while the bundle of wire is being cleared from the machine, a complete revolution of the drive shaft 6 being necessary to perform this latter function. A pin 403 is fixed to the lower end of the lever 202 which carries the feed roller 200. This pin 403 is positioned in a cut-out portion in a rod 404 that has an elongated slot 405 which receives the pin 181. A coil spring 406 is secured between one end of the rod 404 and an arm 407 that is fixed to the leg 4. This spring normally causes the rod 404 to pull on the pin 403 and hold the rolls of the tie wire feeding device tightly together. When the ram 11 and plate 182 are near the end of their forward stroke the pin 181 engages the end of the slot 405 in the rod 404, moving this rod against the tension of the spring 406 and releasing the pressure on the rolls of the tie wire feeding device. While the strands are still holding the lever 389 down the pressure on the feed rollers will be reapplied when the ram and plate move backwards. A cam 408 is carried by an arm 409 that is fixed to the shaft 386. A latch 410 is pivoted near this cam on a pin 411 fixed to the leg 3. This latch has a pin 412 which contacts the cam 408 and has a notch 413 cut in its opposite end. The notched end of this latch is adapted to engage a pin 414 that is fixed to the end of the rod 404. When the strands are shifted past the lever 389, and the lever 390 moves into contact with them, the shaft 386 moves the cam 408 so that the pin 412 on the latch 410 is thrown into a recess in this cam. As the ram 11 now advances and applies the last tie to these strands, the latch 410 will engage the pin 414, thus preventing the rod 404 from again applying the force of the spring 406 to the pin 403 on the end of the lever fixed to the feed roll 200. When the strands are finally cleared from the machine the levers 389 and 390 are forced upward by the counterweight 398, the cam 408 then disengaging the latch 410 from the pin 414, allowing the bar 404 to again apply the force of the spring to the tie wire feeding device.

The aforementioned regulating device also operates to stop the machine when the strands have been discharged therefrom in bundle form. This is done by a short lever 415 that is moved by the shaft 386 and is pivotally connected by a pin 416 to the end of the rod 344. This rod slides on the pin 343, that is fixed to the upper end of the starting handle 342, by means of an elongated slot 417. When the shaft 386 is rotated by the arm 389 the machine is not started as the pin 343 can slide in the slot 417. However, when the arm 389 is forced into its uppermost position

5 by the counterweight 398, this occurring when the strands are discharged, the lever 415 pushes the rod 344 forward until the rear end of the slot 417 encounters the pin 343 and causes the starting handle 342 to move to clutch disengaging position.

10 A chain take-up wheel 418 runs on a stub shaft 419 carried by an arm 420 that is fixed by a bolt 421 to a bracket 422. This wheel 15 may be pressed against the chain 241 to prevent undue slackness.

15 Although I have shown and described a specific form of my invention, in accordance with the patent statutes, I do not intend to limit myself thereto, except as defined by the appended claims.

I claim:

20 1. A rod or wire strand bundling machine including means to interfasten the ends of a tie applied to the strands being bundled and means to insert said ends between said strands.

25 2. A rod or wire strand bundling machine including means to interfasten the ends of a tie applied to the strands being bundled, means to make a path between said strands adjacent said ends and means to move said ends into said path.

30 3. A rod or wire strand bundling machine including means to interfasten the ends of a tie applied to the strands being bundled, a knife constructed and arranged adjacent said ends to move in between said strands to form a path, and a finger constructed and arranged 35 to engage said ends and move them in the path between said strands made by said knife.

40 4. A rod or wire strand bundling machine including means to engage and intertwist the ends of a tie applied to the strands being bundled, means to disengage the ends of said tie from said first named engaging means and means to insert the ends of said tie between said strands.

45 5. A rod or wire strand bundling machine including an arbor having a mouth constructed to receive the ends of a tie applied to the strands being bundled, a knife arranged near said arbor's mouth for movement in between said strands, a member constructed to engage said ends and arranged for movement across said arbor's mouth, and a finger constructed to engage said ends and arranged for movement in between said strands behind said knife.

55 6. A rod or wire strand bundling machine including a ram arranged for reciprocation towards the strands being bundled, an arbor on said ram and having a mouth facing said strands, and a finger swingingly pivotally arranged on said ram for movement past the mouth of said arbor and towards said strands.

60 7. A rod or wire strand bundling machine including a ram arranged for reciprocation towards the strands being bundled, an arbor on said ram and having a mouth facing said

strands, a knife arranged on said ram near said arbor for movement towards said strands, and a finger swingingly pivotally arranged on said ram for movement past the mouth of said arbor and towards said strands.

75 8. A rod or wire strand bundling machine including a ram arranged for reciprocation towards the strands being bundled, an arbor on said ram with a mouth facing said strands and constructed to receive the ends of a tie applied to the latter, a knife arranged on said ram near said arbor for movement towards said strands, a member arranged to move transversely past the mouth of said arbor and constructed to engage the ends of a tie, and a finger swingingly pivotally arranged on said ram for movement past the mouth of said arbor and towards said strands.

80 9. A rod or wire strand bundling machine including an arbor having jaws constructed to receive the ends of a tie applied to the strands being bundled, a lever arranged to operate said jaws, a rotatable member on said arbor and having a cam surface arranged to engage said lever, means to rotate said member in a jaw closing direction more than one revolution and means to rotate said member in the opposite direction a partial revolution subsequent to said first named movement.

85 10. A rod or wire strand bundling machine including an arbor having a mouth constructed to receive the ends of a tie applied to the strands being bundled, means to hold said arbor against rotation with its mouth substantially at right angles to said strands, means to form a path between said strands adjacent the ends of said tie, means to rotate said arbor until its mouth is substantially aligned with said strands, means to hold said arbor in said last named position, a member on said ram constructed to engage the ends of said tie and arranged to move transversely past the mouth of said arbor, and a finger constructed to engage said ends and to move towards the path formed between said strands.

90 11. A rod or wire strand bundling machine including a ram arranged to reciprocate towards the strands being bundled, an arbor on said ram and having a mouth facing said strands, a pivoted knife on said ram near said arbor with an edge towards said strands, a rod having one end in connection with said knife and stationary means to engage said rod.

95 12. A rod or wire strand bundling machine including a ram, means to reciprocate said ram to a point proximate the strands being bundled, a slide on said ram, means to synchronously reciprocate said slide with said ram until said point is reached and then to

continue this reciprocation independently thereof, an arbor on said ram and means to gear said arbor in connection with said slide.

13. A rod or wire strand bundling machine including a ram, a slide on said ram, means to reciprocate said slide, an arbor on said ram with jaws facing the strands being bundled, a lever arranged to operate said jaws, a rotatable member on said ram having a cam surface constructed to engage said lever and means to gear said member in connection with said slide.

14. A rod or wire strand bundling machine including a ram, a slide on said ram, means to reciprocate said slide, an arbor on said ram with a mouth facing the strands being bundled, a rotatable lever on said ram with a spring holding one end thereof against said arbor, a right angular extension arranged in connection with said arbor, means to gear said arbor in connection with said slide, a cam member on said slide and constructed and arranged to engage the free end of said lever as the slide begins to reciprocate, and a slotted member on said slide constructed and arranged to receive said extension as the slide approaches the reversal point of its reciprocation.

15. A rod or wire strand bundling machine including a ram, a slide on said ram, means to reciprocate said slide, an arbor on said ram, a rack on said slide, a segmental gear on said ram and engaging said rack, means to transmit rotary motion from said gear to said arbor, a lug member in connection with said gear and a latch member in connection with said slide, said two last named elements being constructed and arranged to interengage when said segmental gear is moved to rack disengaging position and to then rotate this gear.

16. A rod or wire strand bundling machine including a ram, a slide on said ram, means to reciprocate said slide, an arbor on said ram with jaws facing the strands being bundled and constructed to receive the ends of a tie when applied to the latter, a lever arranged to operate the jaws of said arbor, a rotatable member on said ram and having a cam surface arranged to engage said lever, means including a shaft to gear said rotatable member to said slide so that forward motion of the latter imparts rotation thereto in a direction to close the jaws of said arbor, a cam surfaced member fixed to said shaft and means arranged on said slide to engage said last named member, said two last named elements being constructed and arranged to impart rotation to said rotatable member through said shaft in a direction to open the jaws of said arbor.

17. A rod or wire strand bundling machine including a ram, a slide on said ram, means to reciprocate said slide, an arbor on said ram with a mouth facing the strands

being bundled and constructed to receive the ends of a tie applied to the latter, a pivoted lever on said ram adjacent said arbor, a pivoted finger on said lever having an end constructed to engage the ends of said tie and projecting towards said strands, a rotatable plate on said ram, a connecting-rod between said plate and finger, means on said slide to engage and swing said lever when the slide reciprocates and means on said slide to engage and rotate said plate when the slide reciprocates.

18. A rod or wire strand bundling machine including a ram, a slide on said ram, means to reciprocate said slide, an arbor on said ram with a mouth facing the strands being bundled and constructed to receive the ends of a tie applied thereto, a pivoted lever on said ram near said arbor, a finger pivoted on said lever and having an end projecting towards said strands from near the mouth of said arbor, this end being constructed to engage the ends of said tie, a rotatable plate on said ram, a connecting-rod between said plate and finger, means carried by said slide to engage and swing said lever as the slide advances, means carried by said slide to interengage with said plate to rotate the same as the slide advances and retracts and means carried by said slide to engage and swing said lever as the slide retracts.

19. A rod or wire strand bundling machine including a ram, a slide on said ram, means to reciprocate said slide, an arbor on said ram with a mouth facing the strands being bundled and constructed to receive the end of a tie applied to the latter, a pivoted lever on said ram with a front end towards said strands and a rear end towards said slide, a slotted member on the front end of said member with an end near the mouth of said arbor and constructed to engage the ends of said tie, a pivoted finger on the front end of said lever with an end projection through said slotted member towards said strands and constructed to engage the ends of said tie, a rotatable plate on said ram constructed and arranged to engage the rear end of said lever, a connecting-rod between said plate and finger, means on said slide to engage and swing said lever as the slide advances, means on said slide to interengage and rotate said plate as the slide advances and retracts and means on said slide to engage and swing said lever as the slide retracts.

20. A rod or wire strand bundling machine including means to feed a tie laterally adjacent the strands to be bundled, a tensioned reciprocable guide for said tie, tensioned reciprocable guides for said strands and means to move said strands towards said tie.

21. A rod or wire strand bundling machine including means to feed a tie wire laterally adjacent the strands to be bundled, a ten-

5 sioned reciprocable guide for said wire, tensioned reciprocable guides for said strands, means to move said strands towards said wire, means to slidingly hold said wire on either side of said strands against alined movement therewith and means to sever any excess from said wire remaining beyond said last named means.

10 22. A rod or wire strand bundling machine including means to feed a tie wire laterally adjacent the strands to be bundled, means arranged behind said wire to clamp said strands together, a tensioned reciprocable guide for said wire, tensioned reciprocable guides for said strands, means to move said strands towards said tie to said clamping means, a pair of fingers having ends constructed and arranged to slidingly engage said wire on either side of said strands and means to 20 cut said wire at points adjacent the ends of said fingers.

25 23. A rod or wire strand bundling machine including means to feed a tie wire laterally adjacent the strands to be bundled, means to move said strands towards said wire, a pair of fingers having ends constructed and arranged to slidingly engage said wire on either side of said strands and means to cut said wire at points adjacent the ends of said fingers.

30 24. A strand bundling machine including means to clamp the strands being bundled together, means to encircle said strands with a tie while they are clamped together by said first named means, means to interfasten the ends of said tie, means to insert the ends of said tie between said strands, means to successively shift said strands a predetermined distance laterally between said aforesaid means so that a plurality of ties are applied to the strands thereby and means to discharge said strands when bundled by said application of ties.

35 25. A machine for bundling bunched straight rod or wire strands including means to apply ties to said strands, means to successively shift said strands past said first named means, means to discharge said strands and an upwardly urged lever arranged to be depressed by said strands until the same have been shifted thereby and to control said last named means by its movement.

40 26. A machine for bundling bunched

45 straight rod or wire strands including a shaft positioned parallel to the strands to be bundled, a chain arranged to travel parallel to said shaft, a strand engageable member slidably rockably arranged on said shaft with a depending part constructed to engage said chain when rocked theretowards, means to urge said member away from said chain and means to urge said member towards one end of said shaft.

50 27. A machine for bundling bunched straight rod or wire strands including a ram arranged to reciprocate towards the strands being bundled, means including a sprocket chain and wheel to successively shift said strands laterally past said ram, a ratchet wheel in connection with said sprocket wheel, a dog in engagement with said ratchet wheel, a crank, a connecting rod between said dog and crank and means to revolve said crank during each oscillation of said ram.

55 28. A rod or wire strand bundling machine including a ram arranged to reciprocate towards the strands being bundled, means to successively shift said strands past said ram and means to prevent said strands being shifted by said first named means.

60 29. A rod or wire strand bundling machine including a ram arranged for reciprocation towards the strands being bundled, an arbor on said ram with a mouth facing said strands and constructed to receive the ends of a tie, means to position a tie laterally adjacent the side of said strands opposite said ram, means behind said tie to clamp said strands together, means to reciprocate said ram to a point beyond said tie, a pair of fingers constructed and arranged to engage the portions of said tie on either side of said strands and to bend these portions thereabout so their ends are received by the mouth of said arbor, a knife on said ram with an edge substantially parallel with said strands and arranged for movement therebetween, means to rotate said arbor, means to remove the ends of said tie from the mouth of said arbor and a finger on said ram constructed and arranged to engage the ends of said tie and move in between said strands behind said knife.

65 In testimony whereof, I have hereunto set my hand.

WILLIAM E. GEDDES.
